MACHINE FOR CLEANING CARPETS, GARMENTS, AND THE LIKE

Hjalmar Hammarling, Stocksund, near Stockholm, Sweden

Application April 9, 1936; Serial No. 73,529
In Sweden April 17, 1935

6 Claims. (Cl. 15—89)

This invention relates to that type of machines for cleaning carpets, garments and the like, in which the cleaning operation is effected by means of a beating element or elements carried by a swinging lever or levers or formed by such a lever or levers, the working stroke of said element or elements being performed under the action of springs or by another power whereby sufficient speed and energy may be imparted to the beating element or elements to allow it or them to exert an effective beating action. In machines of this character it is practically impossible to avoid the machine running light at times. As in such no-load running the beating element is not checked by any article to be cleaned, it will pursue its working stroke as far as the construction of the machine and the material used permit. In order to prevent the beating element or the parts carrying and driving same from being deformed or destroyed when this occurs, means must be provided to check the motion of the beating element as it reaches a predetermined position during its working stroke. This may be obtained in the most simple way by the provision of an elastic stop in the path of the swinging lever or levers at such a distance from the free end of said lever or levers as not to allow the portion of the beating element projecting beyond the stop to perform any additional vibrations that might be detrimental to their strength. As the speed of the lever or levers in hitting the stop will, necessarily, be rather high and the beat, moreover, will be concentrated to a single point of the lever, a loud cracking sound will result and, furthermore, the lever or levers runs or run the risk of being deformed at the point thereof engaging the stop. These inconveniences reduce to a great extent the applicability of the machine.

The present invention has for its purpose to provide means whereby to check the motion of the beating element when running light in such a way as to give rise to no disturbing noise at all or only to a very slight noise, at the same time successively absorbing or consuming the kinetic energy of the beating element so as to reduce the stress on the levers as well as on the other parts of the machine to a negligible amount.

In the accompanying drawings one embodiment of a machine according to this invention is illustrated. Fig. 1 is a schematic representation of the principle upon which the invention is based. Fig. 2 is a cross section of the machine, Fig. 3 is a longitudinal section on the line III—III of Fig. 2, and Fig. 4 is a perspective view of a

machine according to the invention as hanging on a rail.

With reference to Fig. 1, the reference character S indicates a lever or arm pivoted at a point a, said lever carrying a beating element p at its free end. The small circles b, c, d, e represent a number of rigid stops situated at equal mutual distances, each representing a fifth of the length of the arm. The arm should be made from a material of great elasticity, as steel, and should be so dimensioned as to be capable of a considerable bending movement under the influence of the kinetic energy that corresponds to the beating force. The operation is as follows: The direction of movement of the beating element during the working stroke is indicated by the arrow and its normal final position in beating is indicated by a—p₁. Let it be assumed that the beating element does not meet with any obstacle at p₁, as represented by a carpet or another article to be cleaned, it will, of course, continue its movement in the direction of the arrow, and as it reaches the position a—p₂ it will come into engagement with the first stop b. Assuming the arm were stiff, which may be possible, theoretically at least, the swinging motion would cease in this position (b—p₂); and the total kinetic energy of the beating element and arm would be transformed into work appearing as a pressure upon the stop b. As a matter of fact the arm, however, is flexible and, therefore, the result will be that only the portion a—b of the arm is brought to a standstill, whereas the portion b—p₂ thereof together with the beating element tends to swing further while holding its amount of energy practically undiminished, until the arm reaches the stop c. During the said last mentioned swinging motion work is performed, as represented by the bending of the arm, which results in a corresponding reduction of the kinetic energy. By suitably placing the stops it is possible to determine beforehand, the part of the energy to be absorbed at each point of the arm. Thus, for instance, it may be predetermined that the portions b—c, c—d, d—e and the extreme free portion (e—p₅) should each absorb a quarter (1/4) of the kinetic energy by their bending work. It is thus evident that when the arm has completed its bending stroke up to the curved line, as represented by the points a, b, c, d, e and p₅, the total kinetic energy is absorbed and the arm will then tend to return to its original state, provided its elastic limit has not been exceeded, which would result in a permanent deformation.

For any given predetermined final speed of

the beating element when hitting the article to be cleaned, it is thus possible to determine by calculation the kinetic energy at the hitting moment and thus also the power necessary for checking the beat at any distance from the center of oscillation, provided the mass of the beating element is known. Knowing the moment of inertia and the modulus of elasticity of the arm, it is easy to calculate the deflection x at the various stops. By setting off this measure from the line $a-p_2$ in the direction of movement of the arm, it is possible to determine the ideal curved line along which the tension of the arm can be released without producing any essential shock against the stops.

The bending work of the material takes place entirely soundless. To suppress the noise at the stops it is necessary to reduce the shocks, as above explained. At the first stop the shock may be reduced to a minimum by placing said stop in close proximity to the centre of oscillation where the speed of the arm is very low. This procedure is repeated along the entire bending line by placing each individual stop as near to the preceding one as possible. Extracting the consequence of this method it is seen, that the ideal bending line will be a convex curve facing the arm which extends from the exact theoretical centre of oscillation. If that portion of the arm which is subjected to the bending stress presents the same cross section area and, consequently, the same moment of inertia at all points, then the bending line will be an arc, the smallest permissible radius of which may be calculated, provided the modulus of elasticity and the permissible stress on the material are known. Fig. 2 shows by dotted lines how the arm is allowed to swing out to its extreme bent position as determined by the stop.

Because difficulties may be experienced, if the point p_5 is allowed to swing out too far from the normal beating position $a-p_1$, this swinging motion should be reduced as far as possible which may be realized by making only a very short portion of the arm flexible as reckoned from the centre of oscillation. This object may be obtained in the best way by forming the respective portion of the arm as a laminated spring, as shown in Fig. 2.

In the beating machine shown in Figs. 2 and 3, a single curve-shaped stop is provided for each oscillating arm. The beating element comprises a rod 1 which is mounted to oscillate parallel to itself through an aperture in the upper or front wall 2 of a casing 3 containing the beating machine. To this end said upper or front wall may wholly or partially comprise a latticework. The rod 1 is carried by a set of arms 4 mounted to swing on shafts 5 lying in alignment, the hub portions 6 of said arms being provided with rearwardly extending projections carrying journals 7 and rollers 8 mounted thereon. Engaging the exposed ends of the journals 7 are coiled spring 9 adapted to effect the working stroke of the arms. The other ends of said springs are attached to arms 10 carried by a shaft 11 which may be turned by means of a crank and handle 12 for adjusting the tension of the springs. The return stroke of the arms is effected by means of cams or eccentrics 13 carried by a driven shaft 14 which are engaged by the rollers 8. The driven shaft 14 is connected by a toothed transmission gear 15 to the shaft of a power motor 16. The motor and the transmission gear are enclosed within an

inner casing 17 to prevent the dusty air contained in the outer casing 3 from entering the inner casing.

The portion of each arm 4 nearest to the respective oscillating shaft 5 comprises, as already stated, a laminated spring 40. In front of each such spring there is a stop 18, Fig. 2, secured to the wall 2 of the casing 3 which is rounded towards the spring by a convex surface 19 extending from a point coinciding with or adjacent the axis of the shafts 5 to another point near the aperture of the wall 2. The surface 19 is formed in conformity with the principles above set forth.

The outer shape of the casing 3 conforms with the outline as determined by the machine elements contained within the box therein as well as by the path of the oscillating rod 1. In order to avoid vibrations in placing the casing on a rigid support and in order to avoid the noise resulting, the casing may, preferably, be mounted to hang on a rail 20 by means of suitable bearings 21 attached to the uppermost corner of the box, as shown in Fig. 4. In this case the rails may also act as an additional support for those portions of a carpet or other article to be cleaned which extend beyond the ends of the casing. An adjustable and, preferably, resilient stay 22 may be provided between the casing and the floor in order to maintain the casing in desired position, that is to say, so that the side 2 thereof will obtain the most appropriate inclination for each individual part of article to be cleaned. This is due to the fact that the inclination is utilized for effecting an automatic feeding of the articles, and in determining same care should be taken of the weight of the articles. Likewise, it is a well-known experience from manual beating that the beat should, preferably be more weak in respect of garments and lighter articles than it ought to be in respect of thick carpets or rugs, and it is for that reason that an adjustment of the tension of the springs should be made.

In operation, the article to be cleaned is placed on and fed over the support as represented by the inclined wall 2. The oscillating beating element will now be checked by the article, before it reaches the curved stop 18 or, at any rate, while it is still in contact with the portion thereof nearest to the shafts 5. At no load the arms, on the contrary, are allowed to continue their oscillation, until they reach the curved stop 18, as indicated by dotted lines in Fig. 2. Due to the curvature of the stop surface 19 the motion of the arms will be checked practically soundless. 45 50

It is to be noted that the invention may also be applied to beating machines of a design or designs different from that shown in the drawings, as for instance, to a machine in which the beating element or elements is or are represented by 60 one or more oscillating arms themselves.

What I claim is:

arms progressively from the axis of oscillation of the arms outwardly.

2. In a machine for cleaning carpets and the like, a frame including a support for the article to be cleaned, beating elements comprising oscillatable arms mounted in the frame, each of said arms being flexible along portions of its length, a rigid stop device secured to the frame, said stop device comprising a convex stop surface situated in the path of movement of the arms and extending in a direction from the axis of oscillation of the arms, said surface being situated so as to be engaged by the flexible portions of the arms in the outswinging movements thereof, for the purpose of checking said movements of said arms progressively, reckoned from the axis of oscillation of the arms outwardly, springs for swinging the beating elements towards the stop device, and cam discs for moving the beating elements backwardly from the stop device.

3. In a machine for cleaning carpets and the like, a frame including an apertured inclined wall for supporting articles to be cleaned, beating elements comprising oscillatable arms mounted in the frame, each of said arms being flexible along portions of its length, and a rigid stop device secured to the frame, said stop device comprising a convex stop surface situated in the path of movement of the arms and extending in a direction from the axis of oscillation of the arms to be engaged by the flexible portions of the arms in the outswinging movements of said arms, for the purpose of checking said movements progressively reckoned from the axis of oscillation of the arms outwardly.

4. In a machine for cleaning carpets and the like, a frame including an apertured inclined wall for supporting articles to be cleaned, beating elements comprising oscillatable arms mounted in the frame, each of said arms being flexible along portions of its length, a transversely extending rod carried by said arms, and a rigid stop device secured to the frame, said stop device comprising a convex stop surface situated in the

path of movement of the arms and extending in a direction from the axis of oscillation of the arms to be engaged by the flexible portions of the arms in the outswinging movements thereof, for the purpose of checking said movements progressively reckoned from the axis of oscillation of the arms outwardly.

5. In a machine for cleaning carpets and the like, a frame including an apertured inclined wall for supporting articles to be cleaned, beating elements comprising oscillatable arms mounted in the frame, the portions of said elements adjacent to the axis of oscillation of the arms comprising laminated springs, and a rigid stop device secured to the frame, said stop device comprising a convex top surface situated in the path of movement of the arms and extending in a direction from the axis of oscillation of the arms and being situated in the paths of movement of said laminated springs in the outswinging movements of the arms, for the purpose of checking said outswinging movements progressively from the axis of oscillation of the arms outwardly.

6. In a machine for cleaning carpets and the like, a frame including an apertured inclined wall for supporting articles to be cleaned, beating elements comprising oscillatable arms mounted in the frame, the lowermost portions of each of said arms, next to the axis of oscillation of the arms, comprising a laminated spring, a transversely extending rod carried by said arms, a rigid stop member secured to the frame, said stop member having a convex stop surface situated in the path of movement of the arms and extending from the axis of oscillation of the arms and being situated in the paths of movement of the laminated springs in the outswinging movements of the arms, for the purpose of checking said movements progressively reckoned from the axis of oscillation of the arms, springs to swing the arms towards said stop surface, and cam discs to move the arms from said stop surface.

HJALMAR HAMMARLING. 45
